MOLD

Filed July 30, 1929

UNITED STATES PATENT OFFICE

GUILDFORD R. HARRILD, OF YAKIMA, WASHINGTON

MOLD

Application filed July 30, 1929. Serial No. 382,168.

My invention relates to molds and more particularly to molds for molding butter and other similar substances prior to cutting the same into squares.

5 An object of the present invention is to provide a mold wherein the side and end walls may be adjusted laterally so as to facilitate dumping of the mold.

Further the invention provides a mold of 10 this character which is durable in construction and will withstand moisture and rough treatment to which the mold is subjected.

With the preceding and other objects and advantages in mind, the invention consists in 15 the novel combination of elements, constructions and arrangements of parts and operations to be hereinafter more fully described, claimed and illustrated in the accompanying drawings, wherein:

20 Figure 1 is a top plan view of a mold constructed in accordance with my invention;

Fig. 2 is a fragmentary vertical section taken on line 2—2 of Fig. 1;

Fig. 3 is a fragmentary bottom plan view 25 of the same; and

Fig. 4 is a fragmentary elevation of a slightly modified embodiment of the invention.

Referring to the invention in detail a rectangular bottom 5 having bevelled edges 6 is 30 provided. Side walls 10 arise from the longitudinal edges of the bottom 5 while end walls 11 arise from the remaining edges of the bottom. The inner faces of the side walls at 35 their lower edges are formed with longitudinally extending recesses having a bevelled side wall 7 opposed to the bevelled edges 6 and a right angular upper wall or shoulder 7a, the latter resting upon the upper face of 40 the bottom 5, and constituting fulcrum points for the walls.

Extending along the lower edges of the side and end walls and upon the outer faces of the latter are cleats 8. Relatively long bolts 9 45 extend transversely through the cleats and associated walls. These bolts extend through longitudinal bores 10a formed in the bottom between its upper and lower faces. At the inner ends of the bores 10a recesses 11 are 50 formed in the under face of the bottom into

which the ends of the bolts project. Nuts 12 are accommodated in these recesses and are engaged with the bolts to maintain tension on the lower ends of the side and end walls.

Reinforcing rails substantially L-shaped in 55 cross section embrace the upper edges of the walls 10 and are secured thereto by dowel pins 14. As disclosed particularly in Fig. 1 the rails have one side bevelled as indicated at 15, and some of the dowel pins extend at 60 an oblique angle with respect to the vertical.

The upper edges of the end walls are provided with rails 16 identical to the rails 13 and which are provided with lateral extensions 16a which project beyond the side walls 65 10. Recesses 17 are provided in the inner faces of the rails 16 for the reception of the ends of the rails 13. Each of the recesses 17 has one of its side walls bevelled in the same plane as the bevelled ends 15 as indicated at 70 18.

The extensions 16a at each side of the mold are provided with longitudinally aligned horizontally extending bores 19 through which a rod 20 passes. One end of each of the rods is 75 threaded into a disk 21 secured to the outer face of the extensions of one of the rails 16. The opposite ends of the rods pass through the extensions of the other rails 16 and are provided with wing nuts 21 which are adjustable to place the rods under tension or produce slack therein. By threading the rods 20 into the disks 21 splitting of the extensions is prevented when the ends are subjected to torque due to tightening of the wing 80 nuts.

Normally the wing nuts are adjusted against the adjacent rails 16 to maintain the rods under tension and thereby hold the side and end walls in a true perpendicular position. When it is desired to dump the mold the wing nuts are loosened. Incident to loosening of the wing nuts the walls swing to the angular position disclosed in dotted lines in 90 Fig. 2. This movement of the walls is had by reason of the lower ends being under tension of the bolts 9 and the parts 7 constituting fulcrums for the walls. In other words, when the rods 20 are slackened the side and end walls swing outwardly to an inclined position.

tion, thus facilitating dumping of the mold contents.

When the winged nuts are adjusted to tension the rods the end walls are drawn towards each other and as they move the bevelled walls 18 of the recesses 17 ride over the bevelled surfaces 15 of the rails 17 and cause the side walls to move inwardly to the upright position.

10 In the modification disclosed in Fig. 4 the ends of the rails 13 are rounded at one side as indicated at 22 and one side of the recesses 17 are similarly shaped to receive the ends of the rails. In this form of the invention circular wear plates 23 are secured to the outer faces of the rails to prevent wear by the wing nuts 21, and to permit the latter to turn freely.

What is claimed is:

1. In a mold, a bottom, side and end walls arising therefrom, said side and end walls being provided with a shoulder on the inner face thereof adapted to rest upon the bottom and to permit the walls to fulcrum thereon, said walls being spaced from the edge of said bottom below the fulcrum points, bolts engaging the lower ends of the walls and bottom to normally urge the latter outwardly to an inclined position, and means carried by the walls for maintaining the same in a perpendicular position.

2. In a mold, a bottom, side and end walls arising therefrom, shoulders formed on said side and end walls whereby they may be fulcrumed on said bottom adjacent their lower ends, said bottom having its edges bevelled whereby the walls will be spaced from said bottom below the fulcrum points thereof, bolts engaging the lower ends of the walls and bottom to normally urge the latter outwardly to an inclined position, and means carried by the walls for maintaining the same in a perpendicular position, said means being releasable to permit the walls to assume such inclined position when it is desired to dump the mold contents.

3. In a mold, a bottom, side and end walls arising therefrom, and pivotally mounted thereon to permit the walls to swing outwardly to an inclined position, and cooperating means carried by the side and end walls whereby to move all of such walls to a perpendicular position.

4. In a mold, a bottom, side and end walls arising therefrom and pivotally mounted thereon, means for tensioning the lower ends of the walls to cause them to swing outwardly at an inclined position, the end walls having recesses at their upper edges, each of which has a bevelled surface, the ends of the side walls also having bevelled surfaces, and means for adjusting the end walls towards each other whereby the bevelled surfaces will cooperate to move the side walls to a perpendicular position.

5. In a mold, a bottom having bevelled

edges, side and end walls arising from the bottom and having bevelled surfaces at their lower edges which are opposed to the first named bevelled edges, the bevelled surfaces of the side and end walls affording lateral shoulders which rest upon the bottom, the bevelled edges of the bottom being opposed to the bevelled surfaces of the walls and spaced therefrom to permit the walls to fulcrum on the bottom, the bottom having recesses in its under face, bolts passing through the lower edges of the walls and engaged with the bottom and extended into the recesses, fastening elements in the recesses and engaging the bolts, and means associated with the walls at their upper edges for drawing them inwardly and normally maintaining them in a perpendicular position, such means being operable to permit the walls to fulcrum on the bottom and assume an inclined position.

6. In a mold including a bottom and side and end walls, said walls having a recess in their lower ends and a shoulder formed with said recess, said shoulder being adapted to rest upon the mold bottom to provide a fulcrum mounting for said walls, said walls being spaced from the edge of said bottom below the fulcrum points thereof, and means for securing said walls to said bottom adapted to permit said walls to assume an inclined position relative to said bottom.

7. In a mold including a bottom and side and end walls, a shoulder formed on the inner face of said walls adjacent the lower end thereof, said shoulders resting on said bottom, said walls having their lower ends bevelled below said shoulders whereby to space said ends from said bottom below said shoulders, and means for securing said walls to said bottom adapted to permit said walls to assume an inclined position relative to said bottom.
